LOCK MECHANISM

Gerrit D. Hill, Rochester, N. Y., assignor to
Sargent & Greenleaf, Inc., Rochester, N. Y.,
a corporation of New York

Application April 21, 1931, Serial No. 531,736

16 Claims. (Cl. 70—26)

This invention relates to a lock mechanism which may be used, for example, in connection with a safe or vault. An object of the invention is the provision of lock mechanism of simple character, having relatively few moving parts, employing no clockwork, springs, escapement, or gears, which cannot be circumvented from the outside of the safe or vault.

Another object of the invention is the provision of a lock mechanism operative to release a bolt or the like after a predetermined time interval, which mechanism is simple and relatively inexpensive to construct, which is accurately timed, and which is fully automatic so that no springs need be wound and no settings need be made previously in order to insure proper operation of the timing mechanism at the desired time.

A further object is the provision of such a time lock mechanism in combination with another lock, so that operation of the other lock will initiate operation of the time lock mechanism.

To these and other ends the invention resides in certain improvements and combinations of parts, all as will be hereinafter more fully described, the novel features being pointed out in the claims at the end of the specification.

In the drawings:

Fig. 1 is an elevation of the inside face of a safe door showing the application of one embodiment of the present invention thereto;

Fig. 2 is a fragmentary view of some of the parts shown in Fig. 1, illustrating them in a different position;

Fig. 3 is a fragmentary view of part of the apparatus shown in Fig. 1 on a larger scale, with parts in vertical section;

Fig. 4 is a vertical section illustrating a detail of one embodiment of the time lock mechanism, and

Fig. 5 is a similar view illustrating details of another embodiment of the invention.

Similar reference numerals throughout the several views indicate the same parts.

In Fig. 1 there is shown diagrammatically a door 11 of a safe or vault, the door having bolts 12 mounted thereon, connected to each other by a bar 13 which in turn is connected to a horizontal bar 14. The bar 14 thus forms part of the bolt-work of the safe and, as it controls the movements of the bolts 12, the member 14 may itself be described broadly as a bolt.

A handle spindle 15 passing through the safe door 11 is provided with a handle 16 on the exterior of the door, and with an arm 17 on the interior of the door. The arm 17 engages a slot 18

within the member 14 so that by turning the handle 16 the member 14 and the bolts 12 may be moved back and forth from locking to unlocking position, and vice versa, whenever such movement is not obstructed by one or another of the lock mechanisms employed.

At 20 there is illustrated conventionally a casting of a combination lock of any usual or ordinary construction having the usual operating spindle 21 connected to the usual knob on the outside of the door. A disk 22 is fixed to the spindle near the inner end thereof. When the tumblers have been properly set by manipulation of the knob, the bolt 23 of the combination lock may be withdrawn so that it no longer obstructs unlocking movement of the boltwork of the door.

Also mounted on the inner face of the door 11 there is a time lock mechanism of novel and greatly simplified form, which in the present preferred embodiment employs no springs, gears or clockwork, and which is simple and comparatively inexpensive to construct. This time lock mechanism operates on the general principle of trapping a quantity of fluid and then releasing this fluid at a predetermined relatively slow rate, so that it takes a predetermined time interval for a given quantity of the trapped fluid to escape. After the predetermined quantity has escaped, and not until then, the mechanism is moved to unlocked position so that the boltwork or other desired parts controlled by the time lock mechanism may be moved in the desired way.

The term "fluid" as used here and in the accompanying claims is intended in a broad sense and is meant to include not only substances which are technically fluids, such as liquid and gas, but also solid substances of relatively small size which collectively are capable of flow somewhat like fluids.

Preferably the fluid which is trapped and slowly released is sealed in place by a heavier fluid. The apparatus here illustrated by way of example has been designed to use a gas as the lighter fluid which is trapped, and a liquid as the heavier fluid which holds it in place. Obviously other forms of apparatus may be made falling within the spirit of this invention, without necessarily using a liquid to seal a gas.

The present apparatus has also been designed to use ordinary air as the gas which is trapped, and mercury as the liquid which seals the gas, but these features likewise, while they are preferred in the present instance, are not to be considered controlling and may be discarded without departing from the spirit of the invention.

The present preferred embodiment of the time lock mechanism, as best illustrated in Fig. 3, comprises a receptacle 25 suitably secured to the inside of the safe door 11, which receptacle 25 has an opening in the bottom which is closed by a closure member 26 extending upwardly like a plug so as to leave a narrow annular space 27 between the plug-like central portion of the closure member and the surrounding wall of the receptacle. This annular space 27 is filled with suitable sealing liquid, such as mercury. At the top of the receptacle 25 there is provided an aperture 28 through which a stem 29 extends loosely. To the lower end of this stem inside the receptacle 25 there is fixed a chamber 30 which may be described in general as inverted cup like, or of an inverted cup shape. As will be clearly seen from the drawings, the chamber 30 has a substantially flat top through which the stem 29 extends and to which it is secured with an air tight connection. The side walls of the chamber are preferably substantially cylindrical and of such size and so positioned that they may move up and down freely in the annular space 27 above described. The cross sectional shape of the chamber as cut by a substantially horizontal plane may be circular, oval, rectangular, or of any other form desired.

From the parts thus far described it will be readily understood that air or any other suitable gas may enter the receptacle 25 through the aperture 28, since the stem 29 passes loosely through it without a tight fit. Whenever the chamber 30 is raised to such a position that the lower edge 31 thereof is above the liquid level 32 of the mercury or other sealing liquid employed, then air or other fluid may enter and fill the interior of the chamber 30. Then if the chamber be dropped slightly downwardly until the lower edge 31 thereof is slightly immersed in the sealing liquid, the fluid trapped in the chamber will be sealed therein and cannot escape in the way in which it entered. Some slight downward movement of the chamber 30 may take place until the trapped fluid is compressed to an extent sufficient to equalize the pressure caused by the weight of the chamber 30 and parts supported thereby, but when the equilibrium is reached it is obvious that no further downward movement of the chamber can take place unless and until some of the trapped fluid is released from the chamber.

According to the present invention the trapped fluid is released at a predetermined rate, so that after the above mentioned point of equilibrium has been reached the chamber 30, stem 29, and associated parts may continue to settle downwardly at a definite predetermined rate depending upon the rapidity with which the trapped fluid escapes. Mechanism is provided so that as long as the chamber 30 is at or above a predetermined position, the member 14 of the boltwork cannot be moved to unlocking position, but as soon as the chamber 30 reaches or drops below the predetermined position, then the boltwork is released and may be unlocked. Hence, it follows that after the chamber 30 has been charged with trapped fluid and released so that it may begin to descend, the boltwork 14 remains locked for a predetermined time interval. This time interval is the length of time necessary for a sufficient amount of the trapped fluid to escape from the chamber 30 so that the chamber moves downwardly to the predetermined unlocking position.

Thus this mechanism may be described as fluid

controlled means for keeping the bolt in locked position for a predetermined time interval.

Preferably the means for releasing the trapped fluid from the chamber is adjustable so that the rate at which the fluid escapes may be varied, and thus the time interval during which the time lock is effective may likewise be adjusted or varied. In this way the mechanism may be set to be effective for a period of from a few moments up to several hours, as desired.

The fluid releasing means in its preferred form comprises a passageway 35 (Fig. 4) in the stem 29 communicating at its lower end with the interior of the chamber 30. The fluid escaping from the chamber flows upwardly through this passageway to an enlargement 36, and thence out through a lateral vent 37. The stem 29 is hollow from the enlargement 36 on up to its top, and is threaded as indicated at 38. A member 39 threaded to cooperate with the threads 38 carries a needle valve 40 at its lower end, which controls the flow of fluid through the passageway 35. By means of a long screw driver inserted in the hollow stem 29 through its top and engaging the usual screw slot in the top of the member 39, the latter may be turned to adjust it up or down and thus to adjust the needle valve 40 to permit fluid to be released through the passageway 35 at any desired rate.

Another possible embodiment of means for controlling the release of the fluid employs a porous plug, as illustrated in Fig. 5. Here the stem 29a has a somewhat larger passageway 35a communicating with the interior of the chamber 30, and leading to an enlargement 36a in the stem, which enlargement communicates with a vent 37a passing through the wall of the stem. A shoulder 42 is formed at the junction of the passageway 35a with the enlargement 36a, and a porous plug is seated on this shoulder, a gasket 43 preferably being interposed between the plug and the shoulder so as to form a perfectly air tight joint.

The porous plug may comprise, for example, any suitable substance 44 having more or less porosity so that fluid can escape therethrough, which substance is preferably surrounded by a sleeve 45 of metal or other suitable material. Numerous porous materials are known and may be used satisfactorily, some of such materials permitting passage of fluid therethrough relatively rapidly, and others permitting such passage relatively slowly. The porous material may be either a naturally occurring porous mineral, such for example as silicon, or an artificially made product such for example as porous plaster, or any other suitable product or material. When it is desired to vary the length of time during which this time lock mechanism is effective the porous plug may be removed and replaced by another porous plug of a different material, or of a different length of the same material.

To make the porous plug readily removable and replaceable, the stem 29a is made hollow all the way from the shoulder 42 to the top of the stem, and of a sufficient diameter so that the porous plug may be inserted and removed through the top of the stem. After inserting a plug, a coil spring 46 may be placed on the top of the plug and a plug 47 may then be screwed into the top of the stem 29a, to place the spring 46 under compression so that the porous plug is held tightly against the gasket 43 to maintain an air tight joint.

In the form of the invention illustrated in Figs. 3 and 4, the top of the stem 29 is provided

with a relatively wide laterally extending flange 50, with which the operating means cooperates as hereafter described. In the porous plug form of invention illustrated in Fig. 5, a similar flange 50a may be formed either as a part of the stem 29a, or as a part of the closure 47, as desired.

Referring now especially to Figs. 1 to 3 inclusive, a guide 55 is provided on the inside of the door 11. Mounted for substantially vertical movement in this guide, substantially in alignment with the stem 29, there is a blocking member 56, which rests loosely upon the flange 50. When this blocking member is in an elevated position, as illustrated in Figs. 2 and 3, it lies in the path of a lug 57 attached to the bolt member 14, so that the member 14 cannot move leftwardly to an unlocking position. When the blocking member 56 drops downwardly, however, to a position such as illustrated in Fig. 1, then it no longer interferes with movement of the lug 57, and bolt member 14 may then be moved leftwardly to an unlocking position so far as this blocking member is concerned.

It will be seen that if the stem 29 be raised to its uppermost position, it will carry the chamber 30 and the blocking member 56 with it, so that the blocking member will be substantially in the position shown in Figs. 2 and 3, and will prevent unlocking of the boltwork. Likewise the chamber 30 will be substantially in the position shown in Fig. 3, so that it will become filled with fluid.

Now if the stem 29 is released, the chamber 30, stem 29, and locking member 56 will settle downwardly, but the downward movement will be relatively slow, depending upon and controlled by the rate of escape of the fluid trapped within the chamber 30. As the chamber, the stem, and the blocking member descend, the boltwork of the safe will be prevented from being unlocked so long as the top of the blocking member 56 is above the bottom of the lug 57, and not until the top of the blocking member drops below the bottom of the lug, will the boltwork of the safe be released for unlocking.

It is to be especially noted that the blocking member 56 is not rigidly connected to the stem 29, but is loosely connected thereto, preferably simply resting on top of the stem. This is advantageous because if it be attempted to move the boltwork prematurely so as to press the lug 57 against the blocking member 56, this will not strain or injure the time lock mechanism in any way or prevent it from functioning, but will simply tend to tilt the blocking member 56 and will hold it rigidly in its guide 55, while the stem 29 will drop away from the bottom of the blocking member and continue to descend. As soon as the pressure of the lug 57 against the blocking member 56 is removed, the blocking member will drop downwardly in its guide until it again rests on the top of the stem 29.

In case pressure is applied to the blocking member by the lug 57 by a premature attempt to unlock the boltwork, it not only will hold the blocking member stationary in its guide, as above mentioned, but furthermore this will remove the substantial weight of the blocking member from the stem 29, so that there will be less weight tending to depress the chamber 30, and consequently the fluid therein will be placed under less pressure and will escape less rapidly. Hence the time required for the chamber and stem to drop to the predetermined unlocking position will be longer than the normal time which is required

when the blocking member 56 rests upon the stem. Thus the time lock mechanism cannot be circumvented from the outside of the safe, but on the contrary, when a premature attempt to unlock the boltwork is made, the time lock mechanism will run still more slowly rather than faster, and the person attempting to unlock the boltwork prematurely will have a still longer time to wait until the boltwork can be unlocked.

Various means may be employed for initially setting or starting the operation of the time lock mechanism. In the present instance it is found convenient to do this by means of a lever 60 pivoted at an intermediate point 61, and having one end 62 in position to underlie the flange 50 on the stem 29. This end 62 of the lever is made thicker and sufficiently heavier than the opposite end so that when no force is applied to the opposite end gravity will bring the end 62 down to the normal position shown in Fig. 3. The opposite end of the lever 60, to the right of the fulcrum 61, lies in the path of movement of a pin 63 fixed to the disk 22 on the spindle 21 of the combination lock 20. Whenever the spindle 21 is turned to operate the combination lock, the pin 63 will come into contact with the right hand end of the lever 60 and will depress this end to the position shown in Fig. 2, so that the left hand end 62 is raised, and through contact with the flange 50 it raises the stem 29, the fluid trapping chamber 30, and the blocking member 56.

A part of the lever 60 is curved to conform to the arc in which the pin 63 moves, as indicated at 64, so that during a substantial part of the movement of this pin the lever will be maintained in its maximum elevated position shown in Fig. 2. Thus the wear on the lever, caused by repeated contact with the pin, will not occur all at one point, and even after long continued use the lever will still be moved to its maximum elevated position each time that the spindle 21 is given a revolution.

The pin 63 is so placed on the disk 22 that when the combination lock is in its normal unlocked position, with the bolt 23 withdrawn, the pin is near the top of the disk and does not interfere with the return movement of the lever 60 to the normal position shown in Figs. 1 and 3.

In operation, when the safe is locked, the parts are in the normal position shown in Fig. 1 with the boltwork held from being unlocked by the bolt 23 of the combination lock, and with the blocking member 56 depressed to unlocked position. When it is desired to unlock the safe, the combination lock is operated to withdraw the bolt 23. Each revolution of the disk 22 in effecting such operation of the combination lock oscillates the lever 60 and the first such oscillation raises stem 29, chamber 30, and the blocking member 56 to the position shown in Fig. 2. During subsequent revolutions of the stem 21, the lever 60 will again be oscillated so that stem 29 and chamber 30 are brought back to their initial elevated position at each revolution of the spindle 21, although some slight settling of the chamber and stem may take place between successive oscillations of the lever. The last revolution of the combination spindle 21, in operating the combination lock, once more elevates the chamber 30 to its initial position, and then releases it for its downward movement. The final motion of the combination spindle in withdrawing the combination bolt 23 from the position shown in Figs. 1 and 2 to the position shown in Fig. 3 will leave the pin 63 in an elevated po-

sition out of contact with the lever 60, so that this lever may drop by gravity to the position shown in Fig. 3, and will remain there, permitting the chamber 30, stem 29, and blocking member 56 to descend in accordance with the escape of fluid from the chamber.

At this time the parts are substantially in the position shown in Fig. 3. The boltwork of the safe is no longer obstructed by the bolt 23 of the combination lock, but it is obstructed by the blocking member 56, so that the safe cannot be opened. The blocking member moves downwardly together with the stem 29 and the chamber, in accordance with the release of fluid from the chamber, one intermediate position of the parts being illustrated in dotted lines in Fig. 3.

At the end of the predetermined time interval, the length of which is determined by the rate of escape of fluid from the chamber 30, the parts will have settled sufficiently so that the top of the blocking member 56 is below the bottom of the lug 57, and no longer obstructs the boltwork. The handle 16 on the exterior of the safe may then be oscillated to move the boltwork member 14 and the bolts 12 leftwardly to unlock the safe.

The time lock mechanism has been described as set in operation by the combination lock, so as to delay the opening of the safe for a predetermined length of time after the combination lock is operated. While the time lock mechanism is well adapted for use in this connection it should be clearly understood that it is capable also of many other uses, and is not limited in its application to operation by a combination lock. The time lock mechanism may be set into operation, for example, by operation of any form of lock other than a combination lock, such as an ordinary key lock, or operation of the time lock may be actuated by any other suitable means or devices not connected with or dependent upon a lock of any kind. The time lock mechanism may also be arranged, if desired, to be set into operation at the time the safe is locked, so as to prevent it from being opened until a predetermined length of time has elapsed after it was last locked.

As an additional safeguard to prevent the time lock from being circumvented, means is provided for retaining the sealing liquid in the receptacle even if the safe is tipped on its side or upside down, as might be done in the case of a small safe. Such sealing means preferably comprises a baffle member 70 within the receptacle 25 arranged so that even if the receptacle be turned on its side or inverted, the liquid sealing means is kept away from the aperture 28 and cannot flow out through the aperture.

This baffle member 70, as clearly shown in Fig. 3, may be in the form of a cup shaped member of slightly larger size than the chamber 30, fixed securely by a liquid tight joint to the top of the receptacle 25 in such position that the chamber 30 may fit inside the baffle when elevated to its upper position. The cavity within the receptacle 25 is enlarged at 71 around the baffle 70 to provide a cavity of substantial size which will hold the sealing liquid. Hence, if the receptacle 25 be turned on its side or upside down, the sealing liquid will run into the cavity 71 around the outside of the baffle 70, and is thus held away from the aperture 28, so that it cannot escape through the aperture.

While the receptacle is on its side or in its upside down position, the time lock mechanism will

not operate because it depends upon gravity for its operation. As soon as the receptacle is turned back to its normal upright position, the sealing liquid which has been held from escape by the baffle 70 will run back to its normal position in the cavity 27, so that it will properly seal the fluid within the chamber 30, and the time lock mechanism will function in the proper manner.

Usually the space between the stem 29 and the sides of the aperture 28 is sufficient to admit the required quantity of gas to be trapped within the chamber 30. If this space should prove insufficient for that purpose, however, a vent 75 may be provided for admitting gas more rapidly to the receptacle 25 when the chamber 30 is elevated. A strainer comprising porous material 76, such as cotton or the like, may be held in place by a cap 77 over the vent 75, so that any gas entering through this vent is strained and foreign matter is prevented from entering with it. Furthermore if the receptacle is placed on its side or upside down temporarily, the strainer 76 will prevent the sealing liquid from running out through the vent.

Preferably the closure 26 of the receptacle 25 is sealed in such manner that it cannot be removed surreptitiously for the purpose of extracting all or a part of the sealing liquid from the receptacle. This may conveniently be accomplished by holding the closure 26 in place by lug screws 80, each of which has a hole through the head thereof, and a sealing cord or wire 81 may be run through the holes and held by a seal 82 of any suitable kind. Thus if a dishonest employee loosens or removes the closure 26 in order to extract part or all of the sealing liquid and render the time lock mechanism ineffective, or partially ineffective, this fact can be ascertained by inspection of the seal 82, and proper precautions can be taken.

While certain embodiments of the invention have been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. Locking mechanism for safes comprising means for controlling movement of a bolt, said means comprising a chamber enclosing a quantity of fluid, and a porous member through which fluid may escape from said chamber.

2. Locking mechanism for safes comprising means for controlling movement of a bolt, said means comprising a chamber enclosing a quantity of fluid, a passageway through which the enclosed fluid may be released, and a porous member in said passageway for controlling the release of fluid therethrough.

3. Locking mechanism for safes comprising means for controlling movement of a bolt, said means comprising a chamber enclosing a quantity of fluid, a passageway through which the enclosed fluid may be released, a seat associated with said passageway, a porous member mounted on said seat for controlling the release of fluid through said passageway, and resilient means for holding said porous member in cooperative relation to said seat.

4. Locking mechanism for safes comprising means for controlling movement of a bolt, said means comprising a chamber enclosing a quantity of fluid and porous means for controlling

release of fluid from said chamber at a predetermined rate.

5. Locking mechanism for safes comprising means for controlling movement of a bolt, said means comprising a chamber enclosing a quantity of relatively light fluid, a heavier fluid for sealing the relatively light fluid in said chamber, and means for releasing the enclosed light fluid from said chamber.

10. Locking mechanism for safes comprising means for controlling movement of a bolt, said means comprising an inverted cup like chamber for trapping a relatively light fluid, a heavier fluid in which the lower edge of said chamber is immersed to seal said relatively light fluid in said chamber, and means for releasing said relatively light fluid from said chamber.

20. Locking mechanism for safes comprising means for controlling movement of a bolt, said means comprising an inverted cup like chamber for trapping a quantity of gas, a body of liquid in which the lower edge of said chamber is immersed to seal said gas in said chamber, and means for releasing said gas relatively slowly from said chamber.

25. Locking mechanism for safes comprising means for controlling movement of a bolt, said means comprising an inverted cup like chamber for trapping a quantity of gas, a body of liquid, means for raising the lower edge of said chamber above said liquid to admit gas to said chamber and for immersing the lower edge of said chamber in said liquid to seal the gas in the chamber, and means for releasing the gas from the chamber.

30. Locking mechanism for safes comprising a movable member, an inverted cup like chamber for trapping a quantity of gas, a body of liquid in which the lower edge of said chamber is immersed to seal the trapped gas therein, means for releasing gas from said chamber so that the chamber may settle into said liquid, and a blocking member controlled by said chamber for blocking movement of said movable member until said chamber has settled to a predetermined position.

35. Locking mechanism comprising a bolt, a lock for preventing unlocking movement of said bolt, an inverted cup like chamber, a body of liquid associated with said chamber, means effective upon actuation of said lock to trap a quantity of gas in said chamber and to immerse the lower edge of said chamber in said liquid to seal the trapped gas therein, means for releasing gas from said chamber so that the chamber may settle into said liquid, and a blocking member controlled by said chamber for blocking unlocking movement of said bolt until said chamber has settled to a predetermined position.

40. Locking mechanism comprising a movable member, an inverted cup like chamber for trapping a quantity of gas, a body of liquid in which the lower edge of said chamber is immersed to seal the trapped gas therein, means for releasing gas from said chamber so that the chamber may settle into said liquid, a stem secured to said chamber to move therewith, and a blocking member cooperating with said stem and mov-

able therewith for blocking movement of said movable member until said chamber has settled to a predetermined position, said blocking member resting loosely on said stem so that transverse pressure on said blocking member will not prevent movement of said stem and chamber.

45. Locking mechanism comprising a movable member, an inverted cup like chamber for trapping a quantity of gas, a body of liquid in which the lower edge of said chamber is immersed to seal the trapped gas therein, a stem secured to said chamber to move therewith, means within said stem for controlling release of gas from said chamber so that the chamber may settle into said liquid, and a blocking member associated with said stem and movable therewith for blocking movement of said movable member until said chamber has settled to a predetermined position.

50. Locking mechanism comprising a receptacle having an aperture in a wall thereof, a body of liquid within said receptacle, an inverted cup like chamber within said receptacle, said chamber being arranged to have the lower edge thereof immersed in said liquid to trap a quantity of gas, a stem attached to said chamber and passing loosely through said aperture, and means for preventing escape of said liquid through said aperture when said receptacle is inverted.

55. Locking mechanism comprising a receptacle having an aperture in a wall thereof, a body of liquid within said receptacle, an inverted cup like chamber within said receptacle, said chamber being arranged to have the lower edge thereof immersed in said liquid to trap a quantity of gas, a stem attached to said chamber and passing loosely through said aperture, and a baffle wall for holding said liquid away from said aperture when said receptacle is inverted so that said liquid cannot escape through said aperture.

60. Locking mechanism comprising a receptacle, means within said receptacle for trapping a quantity of gas, a vent for admitting gas to said receptacle, gas straining means associated with said vent, a bolt, and mechanism cooperating with said gas trapping means for holding said bolt against movement.

65. Locking mechanism comprising a bolt, a combination lock for preventing unlocking movement of said bolt, an inverted cup like chamber for trapping a quantity of gas, a body of liquid for sealing the trapped gas in said chamber, means for releasing gas from said chamber so that the chamber may settle into said liquid, mechanism controlled by said chamber for preventing unlocking movement of said bolt until said chamber has settled to a predetermined position, and means effective upon actuation of said combination lock to raise said chamber until the lower edge thereof is above said body of liquid in order to admit gas to said chamber and to release said chamber so that it may settle into said liquid in accordance with the release of gas from the chamber.

GERRIT D. HILL.
